The ornamental design for a compact disk and business card holder, as shown and described.

DESCRIPTION

FIG. 1 is a perspective view of a compact disk and business card holder in a partially open position showing my new design;

FIG. 2 is a perspective view thereof in the closed position; FIG. 3 is a left side elevational view thereof in the closed position, the right side being a mirror image thereof; FIG. 4 is a front elevational view thereof in the closed position;

FIG. 5 is a rear elevational view thereof in the closed position;

FIG. 6 is a bottom elevational view thereof in the closed position, the top being a mirror image thereof;

FIG. 7 is a front elevational view thereof in the open position; and,

FIG. 8 is a rear elevational view thereof in the open position.
